Primary Examiner — Kimberly Barnes*Assistant Examiner* — Sarah A Nguyen(74) *Attorney, Agent, or Firm* — Grossman, Tucker, Perreault & Pfleger, PLLC**CLAIM**

The ornamental design of a floor cleaning head component, as shown and described.

DESCRIPTION

FIG. 1 is a left side rear perspective view of a floor cleaning head component, showing the new design; FIG. 2 is a left side view thereof;

FIG. 3 is a right side view thereof; and, FIG. 4 is a top side view thereof.

The broken lines in the drawings depict portions of the floor cleaning head component that form no part of the claimed design.
